Charles S. Hine
Design for Stove.
Filed May 1. 1845.

Pl. 29

UNITED STATES PATENT OFFICE.

CHARLES S. HINE, OF NEW YORK, N. Y.

DESIGN FOR A STOVE.

Specification forming part of Design No. 29, dated May 1, 1845.

To all whom it may concern.

Be it known that I, CHARLES S. HINE, of the city of New York, in the State of New York, have invented, designed, or produced a new and useful Shape or Configuration of a Stove for Heating Apartments; and I do hereby declare that the following is a full and exact description thereof.

In the accompanying drawings, Figure 1 is a perspective representation of my stove, and Fig. 2 an outline thereof as exhibited by a horizontal section through its middle.

The center portion, A, which contains the fire-chamber, is cylindrical, and to this are attached two lateral radiators, which have the form of an ogee at front and at back, as shown at B B. At their ends these radiators are hollow or concave, as shown at C C. The pedestal D is made to harmonize in form with the body of the stove, and has the particular shape or configuration represented in the drawings.

E is the outline of a flue at the back of the stove, ascending from the pedestal, as in many

other stoves; but I do not pretend to describe the manner of arranging the flues for the conducting of the draft, it not being pretended that there is anything new in this part, and, if there were, its description would be inappropriate where shape or configuration alone is concerned, the internal arrangements being a combination of improvements for which patents have been previously obtained. Nor do I intend to ask the protection of the law for the ornamental leafing or figures shown in Fig. 2, this part being left to the fancy or taste of the manufacturer.

What is claimed, therefore, as new, and for which I ask a Patent, is—

The peculiar shape or configuration of the combined fire-chamber, radiators, and pedestals, as herein described and represented.

CHARLES S. HINE.
